United States Patent Office.

CHARLES E. FINKLE, OF NEW YORK, N. Y., ASSIGNOR TO HIMSELF AND R. O. GLOVER, OF SAME PLACE.

Letters Patent No. 77,022, dated April 21, 1868.

IMPROVED METALLIC BASE AND MOULDING FOR HEATING PURPOSES.

The Schedule referred to in these Letters Patent and making part of the same.

TO ALL WHOM IT MAY CONCERN:

Be it known that I, CHARLES E. FINKLE, of the city, county, and State of New York, have invented a new and improved Metallic Heating-Base and Moulding; and I do hereby declare that the following is a full, clear, and exact description thereof, which will enable those skilled in the art to make and use the same, reference being had to the accompanying drawings, forming part of this specification.

This invention relates to the construction and improvement of dwelling-houses and public buildings, and to the facilities for heating or warming the same; and it consists in forming a hollow metallic base (or "mop-board") and a moulding, which shall serve as a vehicle for conveying heat and radiating the same, or as a radiating casing over heating-pipes, whether the pipes be filled with steam or water, as will be hereinafter described.

Figure 1 is a front view of a section of the metallic base, and

Figure 2 is a vertical cross-section.

Similar letters of reference indicate corresponding parts.

A represents the wall of the room, and B the floor.

C is a metallic plate, which is attached to the floor and to the wall, as seen in fig. 2.

This plate may be made in any desired form to represent any kind of moulding, or with a corrugated face, so as to increase the heat-radiating surface.

d represents perforations through the upper portion of this plate, for the escape of the heated air into the room.

E represents a curved plate, which is attached to the back of the plate C, as seen in the drawing, so that a tight chamber, F, is formed between the two, the heated air or the heating-pipes being confined therein.

This inner plate E forms a heat-radiating surface, and is essential when the chamber F conveys a current of heated air, as well as when covering steam or water-pipes. As the heat radiating therefrom is discharged into the room through the orifice d, steam or water may be made to circulate through the chamber F without pipes, proper provision being made in its construction for disposing of the water of condensation in case steam is employed.

But, as before stated, where steam or water is employed as a heating medium, it is designed to confine the same in pipes, and to have the pipes confined in the chamber.

It is not designed to confine the metal casing and chamber to the floor of the room or dwelling, but mouldings around doors and other places may be formed of metal in the manner described, so that the current of heated air, or the pipes containing steam or water, may be conveyed therein to any portion of the building.

In making the connection between rooms in different stories of a dwelling, the pipes or chamber may be carried up in the wall or through the ceiling or under the floors, as may be found most convenient.

The base or moulding may be made in front (when screening pipes) of open or ornamental work, and as an ordinary base for a dwelling or building, or as a conveyer for steam, water, or hot air, or as a shield or cover for pipes containing the same.

Having described my invention, I claim as new, and desire to secure by Letters Patent—

A metallic base or metallic moulding for dwellings or public buildings, when constructed and used substantially as herein shown and described for the purposes specified.

CHARLES E. FINKLE.
